DESIGN FOR A BROOCH OR SIMILAR ARTICLE

Solomon Finkelstein, New York, N. Y.

Application December 7, 1945, Serial No. 124,448

Term of patent 3½ years

(Cl. D45—19)

To all whom it may concern:

Be it known that I, Solomon Finkelstein, a citizen of the United States of America and residing at New York, county of New York and State of New York, have invented a new, original, and ornamental Design for a Brooch or Similar Article, of which the following is a specification, reference being made to the accompanying drawing, forming part thereof.

Fig. 1 is a front view of a brooch or similar article, showing my new design.

Fig. 2 is a side view thereof.

Fig. 3 is a top view of Fig. 1.

I claim:

The ornamental design for a brooch or similar article, substantially as shown.

SOLOMON FINKELSTEIN,
